UNITED STATES PATENT OFFICE.

WALTER F. KOKEN, OF ST. LOUIS, MISSOURI.

HYDROELECTRIC BARBER CHAIR.

Application filed December 24, 1923. Serial No. 682,457.

To all whom it may concern:

Be it known that I, WALTER F. KOKEN, a citizen of the United States, residing at St. Louis, Missouri, have invented a certain 5 new and useful Improvement in Hydroelectric Barber Chairs, of which the following is a full, clear, and exact description, such as will enable others skilled in the art to which it appertains to make and use the 10 same.

This invention relates to chairs of the type that are used by barbers, dentists and other specialists for supporting a person on whom the specialist is operating, and particularly chairs of the kind described in my pending application for patent, Serial No. 622,518, filed March 3, 1923, in which the adjustment of the various parts of the chair can be effected by one hand of the operator 15 in charge of the chair, thereby overcoming the necessity of requiring the operator to manually release a retaining device with one hand and use the other hand to move the part or parts of the chair that are to be 20 adjusted.

One object of my present invention is to provide a novel mechanism for controlling the circulation of the liquid used in chairs of the kind mentioned to actuate the pistons 30 that effect the adjustment of the back and the seat of the chair.

Another object is to provide a novel mechanism for starting and stopping the motor that is used to operate the pump which circulates the liquid that operates the pistons. 35 Other objects and desirable features of my invention will be hereinafter pointed out.

My improved chair is similar in general design to the chair described in my said 40 pending application for patent, in that it comprises a vertically-movable seat that is adapted to be raised and lowered, and adjustable back that is adapted to be arranged in an upright position or an inclined 45 position, mechanism for effecting the vertical movement of the seat and for moving the back relatively to the seat to change the position of the back, consisting of two separate and distinct cylinders 50 equipped with pistons, a motor-driven pump for circulating a non-compressible liquid that acts on said pistons, and a controlling means for said mechanism and pump con-

structed in such a way that it can be actuated by one hand of the operator in charge 55 of the chair, thus leaving the other hand of the operator free to manipulate an instrument that is being used in the work in which the operator is engaged. The controlling means of my present chair is different, however, from the controlling means of the chair described in my said application, in that it consists of a plurality of mechanically-operated valves and a plurality of automatic check valves combined in such a way as to 60 cause the operating liquid to be admitted to and exhausted from the cylinders when a governing element is moved from one position to a different position.

Figure 1 of the drawings is a vertical 70 sectional view of a portion of my improved chair, showing the seat frame, the stem which carries said frame and the vertically-disposed socket or cylinder in which said stem is reciprocatingly mounted.

Figure 2 is a top plan perspective view, 75 illustrating the housing in the seat frame and some of the elements that are arranged inside of said housing.

Figure 3 illustrates the position of the 80 valves and the governing element of the controlling mechanism when the back is being reclined, said figure comprising a top plan view and a vertical transverse sectional view.

Figures 4, 5 and 6 are similar views, showing the valves and governing element of the controlling mechanism arranged to cause the back to move into its upright position, 85 to cause the seat to move upwardly and to cause the seat to move downwardly, respectively.

Figure 7 is a diagrammatic view, showing how the motor and the switch in the motor circuit are electrically connected with 90 the electric supply circuit.

Figure 8 is an enlarged vertical sectional view of the automatic check valves of the controlling mechanism that are associated with the reclining cylinder, said view being 95 taken on the line 8-8 of the top plan view of Figure 3.

Figure 9 is a detail sectional view, taken on the line 9-9 of Figure 10.

Figure 10 is an enlarged vertical sectional view of the switch in the motor cir-

cuit and the governing element that is associated with same.

Figure 11 is a side elevational view, showing the back of the chair arranged in its upright position; and

Figure 12 is a similar view, showing the back reclined.

In the accompanying drawings I have illustrated my invention embodied in a barber's chair of the type that comprises a vertically-adjustable seat A, an adjustable back B that can be arranged in an upright position, as shown in Figure 11, or an inclined position, as shown in Figure 12, an apron C and arms D connected with the back B in such a manner that they will move in unison with the back, a supporting base or standard E provided with a vertically-disposed socket or cylinder F, as shown in Figure 1, and a piston or stem G in said socket connected at its upper end to the seat frame H of the chair. The seat A of the chair is raised by pumping a non-compressible liquid such as oil into the lower end of the socket F in the standard, so as to force the stem G upwardly, and said seat is lowered by permitting the liquid to escape from the socket F. Any suitable kind of pump can be used for circulating the liquid that actuates the stem G of the chair, but I prefer to use a rotary pump I mounted on the seat frame of the chair and operate said pump by an electric motor J which is also mounted on the seat frame of the chair. The means that I prefer to use for moving the back of the chair relatively to the seat consists of a horizontally-disposed cylinder K carried by the seat frame and provided with a piston that is operatively connected by a piston rod 1 and a system of links 2, 3 and 4 to the apron C of the chair in such a way that the outward movement of said piston causes the back, arms and apron of the chair to move into the position shown in Figure 12 and the inward movement of said piston causes said back, arms and apron to move into the position shown in Figure 11. When it is desired to recline the back of the chair the operator actuates a device which sets the pump I in operation and also causes the operating medium to be supplied to the cylinder K in such a way that the piston of said cylinder will move outwardly; and when it is desired to restore the back to its normal upright position, the operator actuates said device so as to cause the operating medium to move the piston in the cylinder K in the opposite direction. The vertical movement of the seat of the chair can also be effected by operating the device just referred to so as to cause the operating medium to be admitted to or exhausted from the cylinder F in the standard of the chair in which the stem G reciprocates.

Controlling means.

The controlling means that governs the circulation of the operating medium consists of a number of automatic check valves, a number of mechanically-operated valves, and a governing element, preferably a rock shaft L, mounted in the seat frame H of the chair and provided with an operating handle M and with means for opening the mechanically-operated valves when said shaft is moved into certain positions. The motor J which actuates the pump I is controlled by a switch combined with the handle M of the governing element L in such a way that when said handle is operated to cause the seat to move upwardly or to cause the back to swing upwardly or downwardly relatively to the seat, the motor will become operative, and when said handle is actuated to bring the seat to rest or to bring the back to rest, the motor will stop automatically, thereby enabling the adjustment of the various parts of the chair to be governed by one hand of the operator. The chair is equipped with a stem holding device for holding the stem against rotary movement, which stem holding device is combined with the governing element L in such a way that it will be rendered inoperative automatically whenever said governing element is moved to effect the adjustment of the seat or the back of the chair and will be rendered operative automatically whenever said governing element is restored to its former position after the desired adjustment of the chair has been made. In order to securely hold the back and apron of the chair in adjusted position, a clamping device N is provided for co-operating with the piston rod 1 of the reclining cylinder K, said clamping device N being so constructed and arranged that it will normally hold the piston rod 1 of the reclining cylinder against movement, but will be released or rendered inoperative automatically whenever the governing element is moved into certain positions.

Valves of controlling mechanism.

The valves of the controlling mechanism comprise four mechanically-operated valves 5, 6, 7 and 8; a double check valve O that is associated with one end of the reclining cylinder K, a double check valve P that is associated with the opposite end of said reclining cylinder and a single check valve 9 that is arranged in the duct controlled by the valve 7. The governing element or rock shaft L, previously referred to, is provided with cams 5^a, 6^a and 7^a that co-operate with the stems of the valves 5, 6 and 7, respectively, to open said valves, and said governing element L is also provided with an arm 8^a, shown in Figure 6, that co-operates with

the stem of the valve 8 to open said valve. The various valves above referred to are mounted in a valve box, designated as an entirely by the reference character R, and

5 provided with ports and passageways through which the operating medium circulates. The particular construction of said valve box is immaterial, so far as my invention is concerned, but one convenient way

10 of constructing said valve box is to form it from a plurality of horizontally-disposed plates arranged in superimposed relation and provided with grooves, openings or cored portions that constitute the ports and passageways for the operating medium. As

15 shown in Figures 3 to 6, inclusive, the valve box R is provided with a chamber 10 common to the three valves 5, 6 and 7 and an inlet duct 11 that leads to said chamber from

20 the discharge side of the pump I. The valves 5, 6 and 7 control outlet ducts 5^b, 6^b and 7^b through which the operating medium escapes from the valve chamber 10 in the valve box R, the duct 5^b leading to the

25 double check valve O, as shown in Figure 3, the duct 6^b leading to the double check valve P, as shown in Figure 4, and the duct 7^b leading to the pipe through which the operating medium is conducted down into the

30 cylinder F in the base of the chair. The double check valves O and P, previously referred to, are of the same design and of the construction illustrated in Figure 8. The valve O comprises a top valve 12 ar-

35 ranged in vertical alignment with a bottom valve 13, a spring 14 that exerts upward pressure on the bottom valve 13 and holds it normally seated and a depending portion 15 on the underside of the top valve 12 that

40 exerts downward pressure on the bottom valve 13 and causes said bottom valve to open when the top valve 12 opens under the influence of the operating liquid escaping from the valve chamber 10 through the outlet duct 5^b. The top valve 12 controls a duct

45 16 that leads to the rear end of the reclining cylinder K, and the bottom valve 13 controls a duct 17 that leads from the front end of said reclining cylinder. The two corresponding top and bottom valves 12^a and 13^a of the double check valve P control a duct

50 16^a that leads to the front end of the reclining cylinder K and a duct 17^a, respectively, that leads from the rear end of the reclining cylinder. The outlet duct 7^b in the valve box that is associated with the valve 7 leads to a vertically-disposed pipe 18 in the stem C of the chair that projects downwardly through the lower end of the stem, as shown

55 in Figure 5, and the mechanically-operated valve 8, previously referred to, controls a port in the valve box through which the operating liquid escapes into the sump from which the pump draws its supply of liquid.

60 In the chair herein shown the hollow stem

G constitutes the sump and the liquid is withdrawn from said sump through a vertically-disposed pipe 19 whose upper end communicates with a duct 20 in the valve box that leads to the intake of the pump. Preferably, the valve box R is arranged inside of a casing S in the seat frame H of the chair, and said valve box is provided on its exterior with outlet ports through which the operating medium can escape from certain of the ducts in said valve box and enter the casing S, finally draining out of said casing into the hollow stem G of the chair, on the upper end of which the casing S is mounted, as shown in Figure 1.

If it is desired to move the back of the chair from its upright position, shown in Figure 11, into its reclined position, shown in Figure 12, the handle of the governing shaft L is moved into a certain position, which, for convenience, I will refer to as its "reclining" position, so as to start the pump and cause the cam 5^a on the shaft L to move the valve 5 into its open position, as shown in Figure 3. The pump I then causes the liquid in the hollow stem G of the chair to circulate upwardly through the pipe 19 into the pump, then from the pump through the duct 11 into the valve chamber 10, and thence from said valve chamber through the duct 5^b to the double check valve O. The liquid exerts pressure on the top valve 12 of the double check valve O in a direction to cause said top valve to open, and as said top valve moves downwardly, the projection 15 on the underside of same engages the bottom valve 13 and moves said bottom valve into its open position. As soon as said top and bottom valves 12 and 13 open the liquid in the duct 5^b passes into the duct 16 that leads to the rear end of the reclining cylinder K, and the liquid in front of the piston in said reclining cylinder escapes through the duct 17 leading from the front end of the reclining cylinder, past the bottom valve 13 which controls the duct 17, and thence through a port in the exterior of the valve box R, said escaping liquid entering the casing S that surrounds the valve box and finally draining from said casing back into the hollow stem G of the chair. The liquid that is admitted to the rear end of the reclining cylinder K causes the piston in said cylinder to move outwardly, and when the back B of the chair reaches its fully reclined position or any other position into which it is desired to adjust the back, the operator moves the handle M of the governing shaft L into its "neutral" position so as to permit the valve 5 to close, and thus cut off the supply of liquid to the rear end of the reclining cylinder, the switch that governs the motor circuit being so arranged that the pump I will stop as soon as the operator starts to move the handle M from its

70 75 80 85 90 95 100 105 110 115 120 125 130

"reclining" position towards its "neutral" position. The clamping device N, previously referred to, that co-operates with the piston rod 1 of the reclining cylinder K is preferably composed of a rigid jaw 21 and a movable jaw 22 pivotally connected together and arranged so that they will embrace said piston rod 1, as shown in Figures 3 and 4, the movable jaw 22 being normally acted upon by a spring 23, shown in Figure 1, that causes the jaws 21 and 22 to exert sufficient pressure on the piston rod 1 to hold the back and apron of the chair in adjusted position. Various means may be provided for moving the jaw 22 in a direction to release the piston rod 1 preparatory to opening the valve 5, but I prefer to equip the governing shaft L with a cam 24 that co-operates with an extension or arm on the jaw 22 to move said jaw away from the stationary jaw 21 when the handle M is moved into its "reclining" position, as shown in Figure 3, and permit said jaws to clamp the piston rod 1 when said handle is moved back to "neutral" position.

If the operator fails to stop the pump and change the position of the governing shaft L so as to close the valve 5, after the back of the chair has reached its fully reclined position, the liquid will continue to circulate from the valve chamber 10, through the rear end portion of the reclining cylinder K and then escape from said cylinder through a lateral discharge orifice 25 in same back into the sump or hollow stem G of the chair, thereby preventing damage or injury to the mechanism in the event the operator fails to stop the pump after the back has reached its fully reclined position.

To raise the back from its reclined position into its upright position the handle M of the governing shaft L is turned from its "neutral" position into a different position, which, for convenience, I will refer to as its "straightening" position, which operation causes the pump to start and also causes the cam 6^a on the governing shaft L to open the valve 6, as shown in Figure 4. As soon as said valve 6 opens the liquid which is being forced into the valve chamber 10 by the pump I will escape from said valve chamber through the duct 6^b and exert pressure on the top valve 12^a of the double check valve P in a direction to open said top valve and also open the bottom valve 13^a. As soon as said valves 12^a and 13^a open the liquid in the duct 6^b will pass the valve 12^a and flow through the duct 16^a into the front end of the cylinder K, thereby moving the piston of said cylinder rearwardly and causing the liquid behind said piston to escape through the duct 17^a past the valve 13^a, and thence back to the sump or hollow stem G of the chair, it being of course understood that the movement of the handle M of the governing shaft L into

its "straightening" position causes the clamp N to be rendered inoperative so as to release the piston rod 1 of the reclining cylinder. After the back of the chair has reached its upright position or the position into which it is desired to adjust said back, the operator moves the handle M back to its "neutral" position, thus causing the motor to stop and also causing the valve 6 to close. If the operator fails to stop the motor after the back has reached its vertical position, the liquid that is admitted to the front end portion of the cylinder K will escape through the lateral discharge orifice 25 leading from said cylinder, and thus prevent damage or injury to the mechanism.

To raise the seat of the chair the operator moves the handle M of the governing shaft L into its "raising" position so as to set the pump I in operation and cause the cam 7^a on the shaft L to open the valve 7. The pump I will then cause the liquid in the hollow stem G of the chair to circulate upwardly from said stem through the pipe 19 and duct 20 in the valve box, through the pump, then through the valve chamber 10 and then thru the duct 7^b in the valve box that communicates with the vertically-disposed pipe 18 in the stem G of the chair, down through which pipe 18 the liquid passes into the socket or cylinder F, as indicated by the arrows in Figure 5. The upward pressure which the liquid in the socket F exerts on the lower end of the stem G causes said stem and the seat frame to move upwardly, and after the seat has reached the desired elevation, the handle M is moved into its "neutral" position, so as to stop the motor and the pump actuated by the motor and cause the valve 7 to close. The single check valve 9, previously referred to, that is arranged in the duct 7^b which leads from the valve 7 prevents the liquid from backing up through the pipe 18, thereby trapping the liquid in the socket or cylinder F and securely holding the seat frame of the chair in the position into which it has been moved. In order to prevent the mechanism of the chair from being damaged or injured in the event the operator fails to stop the pump and turn the governing shaft L into such a position as to close the valve 7 after the seat frame of the chair has reached its extreme upper position, the socket or cylinder F is provided with a by-pass 26, as shown in Figure 5, that establishes communication between the socket or cylinder F and the hollow stem G when said stem reaches the end of its upward stroke. Consequently, if the pump continues in operation after the seat has reached its extreme upper position, the liquid will continue to circulate from the socket F up through the by-pass 26, upwardly through the pipe 19 to the duct 20 that leads to the intake of the pump and

then from the discharge side of the pump through the duct 11, valve chamber 10, duct 7^b and pipe 18 to the lower end of the socket F of the chair.

- 5 To lower the seat the operator turns the handle M of the governing shaft L into still another position, hereinafter referred to as its "lowering" position, so as to cause the valve 8 to open and permit the liquid in the 10 socket F to pass upwardly through the pipe 18 and be discharged into the stem G by the downward pressure which said stem exerts on the liquid in the socket F, the stem continuing to move downwardly by gravity 15 until it reaches the end of its downward stroke, or until the governing shaft L is turned into such a position that the arm 8^a thereon causes the valve 8 to close. At such times, namely, when the seat is being lowered, the motor and pump are idle, as the 20 weight or load imposed on the stem G of the chair by the seat frame and the occupant of the chair is sufficient to cause the liquid in the socket F to pass upwardly through the 25 pipe 18 and be discharged into the hollow stem G, if the valve 8 is open.

Switch.

The switch that controls the circuit of the 30 motor J is combined with the governing shaft L in such a way that the motor will be started and stopped automatically when the handle M on said shaft is moved into certain positions. In the form of my invention 35 herein illustrated the controlling switch for the motor circuit comprises two contacts 30 arranged in the motor circuit, and a shiftable circuit-closing device 31 that is adapted to snap into engagement with said contacts in three different positions of the handle M. 40 As shown in Figures 1 and 10, the governing shaft L extends through a sleeve 32 on the casing S and the handle M that is rigidly connected to said shaft L is provided with 45 a pivotally mounted catch or holding device 33 that rides upon a flange 34 on the sleeve 32. Said flange 34 is provided in its periphery with four notches, designated in Figure 9 by the reference characters x, y, z and w. 50 The notch x is so arranged that it will receive the catch 33 when the handle M is in its "neutral" position, the notch y is adapted to receive said catch when said handle is in its "reclining" position, the 55 notch z is adapted to receive said catch when the handle is in its "straightening" position and the notch w is adapted to receive said catch when the handle is in its "raising" position. 60 When the handle M is arranged in its "lowering" position the catch 33 will ride on the portion of the edge of the flange 34 at the left of the notch w. The contacts 30, 65 previously referred to, preferably consist of two rings of conducting material mounted on an insulating sleeve 35 that surrounds the

sleeve 32, said rings 30 being equipped with three pairs of projections arranged in alignment with the notches y, z and w, previously referred to, and designated by the reference characters y', z' and w'. When the catch 70 33 is positioned in the notch x, the circuit closing device 31 cannot engage the contacts 30, but when said catch is positioned in either the notch y, the notch z or the notch w, the circuit closing device 31 can engage the projections on the contacts 30 that are associated with said notches. The catch 33 is pivotally mounted between two ears 36 on the hub of the handle M, and the circuit closing device 31 is pivotally mounted on a jointed, spring- 75 actuated structure carried by the ears 36. As shown in Figure 10, the ears 36 are so arranged that they overhang the sleeve 32 in which the governing shaft L turns, thus forming a support for a link 37 that is pivotally mounted on said ears by a pintle 38. A second link 39, which is pivotally mounted on the pintle 38, is joined by a link 40 to the catch 33 and the circuit closing device 31 is arranged at the lower end of the 80 link 41 which is pivotally connected at 42 to the link 37. The two links 37 and 39 are combined with springs 43 which are connected to cross pieces arranged at the outer 85 ends of said links, and the free end of the link 39 is connected to the upper end of two springs 44 whose lower ends are connected to the ears 36 on the hub of the handle M. Normally, the springs 44 exert a downward 90 pull on the free end of the link 39, thus causing the link 40 which is interposed between the link 39 and the catch 33 to exert pressure on said catch in a direction tending to hold it in engagement with the flange 34 on the sleeve 32. At such times the springs 95 43 which join the free ends of the links 37 and 39 together are arranged below the pintle 38 that forms the axis of movement of the links 37 and 39, as shown in Figure 1. When the catch 33 is positioned in the notch x in the flange of the sleeve 32, so as to hold the handle M in its "neutral" position, the circuit closing device 31 will be held out of engagement with the contact rings 30, due to the fact that said notch x is not deep enough 100 105 to permit the catch 33 to move downwardly far enough to cause the link 37 to assume such a position that the circuit closing device 31 will engage the contacts 30. When the catch 33 is arranged in either of the 110 notches z, y or w, however, which notches are deeper than the neutral notch x, the catch 33 will occupy a lower position and the link 37 will occupy such a position that the circuit closing device 31 can engage the 115 120 projections on the contacts 30 that are associated with the particular notch in the flange 34 in which the catch 33 is then positioned. To move the handle M from one position to a different position, the operator 125 130

8
 presses downwardly on the hand piece 45 on said handle, thereby causing a plunger 45^a in the handle to exert pressure on the catch 33 and move it upwardly out of engagement 5 with the flange 34 of the sleeve 32, as shown in Figure 10. When the catch 33 swings upwardly the link 40 exerts a thrust on the free end of the link 39, thereby causing said link to swing upwardly, and, as the free 10 end of said link is joined by the springs 43 to the free end of the link 37, said link 37 will also swing upwardly and move the circuit closing device 31 upwardly away from the contact rings 30 with a quick movement 15 produced by contraction of the springs 43. While the handle M is being moved into its new position the circuit-closing device 31 is held out of engagement with the contact rings 30; but when the handle M reaches its 20 new position, assuming that the catch 33 is in alignment with one or the other of the notches z, y or w in the new position of the handle, the circuit closing device 31 will snap downwardly into engagement with the 25 contact rings 30 as soon as the operator relieves the downward pressure on the handle piece 45, due of course, to the fact that the springs 44 contract as soon as the plunger 45^a moves upwardly under the influence of 30 its actuating spring 46. From the foregoing it will be understood that in my improved chair the operator can control the movements of the various parts of the chair with one hand and can cause the seat to move upwardly or downwardly and can cause the 35 back to move into its reclined position or upright position by simply changing the position of the handle M on the governing shaft L, the switch that controls the motor circuit being combined with the shaft that 40 governs the mechanically-operated valves in such a way that the pump will start and stop automatically with the opening and closing of said valves.

45 *Stem locking device.*

The stem locking device is similar to the stem locking device of the chair described in my pending application previously referred to and consists of a shoe T arranged on the inside of the stem and an actuating device for said shoe formed by a wedge or expanding element T' that is connected by a rod U with a crank arm 47 on the shaft L, said crank arm being so arranged that the shoe T will normally hold the stem against rotary movement, but will be rendered inoperative automatically, thus releasing the stem whenever the handle M is moved from its "neutral" position into one of its various other positions.

Electric conductors.

The conductors that supply electric current to the motor J are also preferably of

the construction described in my said application and consist of two collector rings V arranged on the underside of the casing S in the seat frame of the chair and insulated from said casing, vertically-disposed bars V' reciprocatingly mounted in the standard of the chair and arranged in sliding engagement with contacts V² in the standard to which electric supply wires V³ are connected, the exposed portions of the conductor bars V' being covered with insulating material and each of said bars being provided at its upper end with a shoe or brush V⁴ equipped with a notch that receives one of the collector rings V. A means of the construction above described for connecting the motor with the supply circuit permits the seat of the chair to be raised and lowered and also revolved and there are no loose wires or flexible conductors to interfere with the movements of the operator around the chair or interfere with the adjustment of the various parts of the chair.

Having thus described my invention what I claim and desire to secure by Letters Patent is:

1. A chair provided with a seat, a back, an hydro-electric means for moving the seat vertically and for moving the back relatively to the seat, a locking device for holding the back in adjusted position, a governing element for controlling said hydro-electric means, and means for rendering said locking device inoperative automatically when said governing element is actuated to effect a change in the position of the back.
2. A chair provided with a seat, a back, an hydro-electric means for moving the seat vertically and for moving the back relatively to the seat, a locking device for holding the back in adjusted position, a governing element for controlling said hydro-electric means, and means whereby said locking device will be rendered inoperative automatically when said governing element is actuated to effect a change in the position of the back and will be rendered operative automatically when said governing element is restored to "neutral" position.
3. A chair provided with a seat, a back, an hydro-electric means for moving the seat vertically and for moving the back relatively to the seat, a manually-operable governing element for controlling said hydro-electric means, and a locking device for holding the back in adjusted position combined with said governing element in such a way that movement of said governing element into either one of two different positions causes said locking device to become inoperative automatically and movement of said governing element back to its "neutral" position causes said locking device to become operative automatically.

4. A chair provided with a seat, a back, an hydraulic means for moving the back relatively to the seat to change the position of the back, a manually-operable governing element for controlling said hydraulic means, and a mechanically-operated locking device for holding the back in adjusted position combined with said governing element and adapted to be rendered operative and inoperative automatically by the operation of said governing element.

5. A chair provided with a seat, a back, a piston for moving the back relatively to the seat, means for causing an operating medium to act on said piston, a device that co-operates with the rod of said piston to hold the back in adjusted position, a manually-operable governing element for controlling the operating medium, and a means operated by said governing element for automatically rendering said holding device inoperative.

6. In an adjustable chair of the kind described, a cylinder provided with a piston for effecting the movement of an adjustable element of the chair, a double check valve composed of two valves that control ducts which communicate with the opposite ends of said cylinder, and means for causing both of said valves to open when an operating medium exerts pressure on one of said valves.

7. In a chair of the type described, a cylinder provided with a piston that is used to effect the adjustment of one of the elements of the chair, a double check valve composed of two valves that control ducts which communicate with the opposite ends of said cylinder, a mechanically-operated valve for causing an operating medium to act on one of said check valves to open same, and means for transmitting movement from said check valve to the other check valve so as to cause the operating medium in one end of the cylinder to escape from same when the mechanically-operated valve is actuated to admit the operating medium to the other end of the cylinder.

8. In a chair of the type described, a cylinder equipped with a piston for effecting the movement of one of the adjustable elements of the chair, a double check valve composed of two valves arranged in such a way that the movement of one of said valves into its open position causes the other valve to open, ducts controlled by said valves and communicating with the opposite ends of said cylinder, and means for causing an operating medium to exert pressure on one of said valves to open same and thereafter enter said cylinder.

9. In a chair of the type described, a cylinder provided with a piston for effecting the adjustment of one of the elements of the chair, double check valves associated with

the opposite ends of said cylinder, each of said check valves being composed of one valve that controls a duct which communicates with one end of the cylinder and a separate valve which controls a duct that communicates with the opposite end of the cylinder, means under control of the operator in charge of the chair for causing an operating medium to act on either of said double check valves, and means for causing the two valves of each of said check valves to operate in unison.

10. In a chair of the type described, a cylinder provided with a piston which is adapted to be actuated by an operating medium in said cylinder to effect the adjustment of one of the elements of the chair, a double check valve composed of two separate valves for retaining the operating medium in said cylinder on opposite sides of said piston, a spring that holds both of said valves seated, and means for causing an operating medium from a source of supply to act on one of said valves so as to open both of said valves.

11. In a chair of the type described, a cylinder provided with a piston that is used to effect the movement of one of the adjustable elements of the chair, separate and distinct manually-controlled valves for governing the admission of an operating medium to both ends of said cylinder, and a double check valve associated with each end of said cylinder, each of said double check valves being composed of two valves combined in such a way that the movement of one of said valves into its open position, due to the pressure exerted on same by the operating medium from the source of supply, causes the other valve to open and thus permit the operating medium in the cylinder to escape therefrom.

12. In a chair of the type described, a cylinder provided with a piston for moving one of the adjustable elements of the chair, double check valves associated with the opposite ends of said cylinder and each composed of two valves arranged in longitudinal alignment with each other and provided with co-operating portions that cause said valves to move in unison, said double check valves being so arranged that they trap the operating medium in the opposite ends of the cylinder, and separate and distinct mechanically-operated control valves, one of which control valves is adapted to be opened when it is desired to have the piston move in one direction and the other being adapted to be opened when it is desired to have the piston move in the opposite direction.

13. A chair provided with a back, a seat, separate cylinders equipped with pistons for moving said back and seat, a valve box provided with a chamber to which an operating medium under pressure is supplied, two

ducts leading from said chamber to the opposite ends of said back cylinder, a separate duct leading from said chamber to the seat cylinder for introducing the operating medium into said seat cylinder when it is desired to have the seat move upwardly, control valves for governing the escape of the operating medium from said chamber through said ducts, and double check valves associated with the opposite ends of the back cylinder and each composed of two valves, one of which controls a duct that communicates with one end of the back cylinder and the other controlling a duct which communicates with the opposite end of the back cylinder.

14. A chair provided with a seat, a back, cylinders equipped with pistons for moving the seat vertically and for moving the back relatively to the seat, separate control valves that are adapted to be opened to admit an operating medium to said cylinders, double check valves associated with the opposite ends of the back cylinder and arranged so that they are rendered operative by the pressure of the operating medium being admitted to the back cylinder, a locking device for holding the back in adjusted position, and a manually-operable governing element for actuating said control valves and for causing said locking device to become operative and inoperative.

15. A chair provided with a seat, a back, a socket equipped with a vertically-movable stem that carries the seat, a cylinder equipped with a piston for moving the back relatively to the seat, separate control valves for admitting an operating medium to said socket to raise the seat and for permitting the operating medium to escape from said socket to lower the seat, separate control valves for admitting an operating medium to the opposite ends of said cylinder to recline the back and move the back into its upright position, a manually-operable governing element for actuating said control valves, and automatic double check valves associated with the opposite ends of said cylinder and arranged so that they are rendered operative by opening the control valves which govern the admission of the operating medium to said cylinder.

16. A chair provided with a seat, a back, a socket equipped with a vertically-movable stem that carries the seat, a cylinder equipped with a piston for moving the back relatively to the seat, separate control valves for admitting an operating medium to said socket to raise the seat and for permitting the operating medium to escape from said socket to lower the seat, separate control valves for admitting an operating medium to the opposite ends of said cylinder to recline the back and move the back into its upright position, a manually-oper-

able governing element for actuating said control valves, automatic check valves associated with the opposite ends of said cylinder and arranged so that they are rendered operative by opening the control valves which govern the admission of the operating medium to said cylinder, and a locking device for holding the back in adjusted position arranged so that it will be rendered operative and inoperative by said governing element.

17. A chair provided with a seat, a back, a socket equipped with a vertically-movable stem that carries the seat, a cylinder equipped with a piston for moving the back relatively to the seat, separate control valves for admitting an operating medium to said socket to raise the seat and for permitting the operating medium to escape from said socket to lower the seat, separate control valves for admitting an operating medium to the opposite ends of said cylinder to recline the back and move the back into its upright position, a manually-operable governing element for actuating said control valves, automatic check valves associated with the opposite ends of said cylinder and arranged so that they are rendered operative by opening the control valves which govern the admission of the operating medium to said cylinder, a locking device for holding the back in adjusted position arranged so that it will be rendered operative and inoperative by said governing element.

18. A chair provided with a seat, a back, a socket, a hollow stem in said socket that carries the seat, a cylinder equipped with a piston for moving the back relatively to the seat, a pump for circulating an operating medium that is used to actuate said stem and piston, a valve box equipped with ducts and passageways through which the operating medium is admitted to and discharged from said socket and cylinder, control valves for governing the circulation of the operating medium, and a casing surrounding said valve box that is adapted to receive the operating medium discharged from said valve box and conduct said operating medium into the hollow stem of the chair.

19. A chair provided with a seat, a back, a socket, a hollow stem in said socket that carries the seat, a casing at the upper end of said stem whose interior communicates with the interior of the stem, a cylinder equipped with a piston for moving the back relatively to the seat, a pump for circulating an operating medium that is used to actuate said stem and piston, a valve box in said casing provided on its interior with ducts and passageways through which said operating medium circulates and on its exterior with ports through which the operat-

ing medium escapes into said casing, and control valves in said valve box for governing the circulation of the operating medium.

20. A chair provided with a seat that is adapted to be raised and lowered, a back that is adapted to be moved into a reclined position and into an upright position, a socket equipped with a stem for moving the seat vertically, a cylinder equipped with a piston for moving the back relatively to the seat, a pump for circulating an operating medium that is used to actuate said stem and piston, separate control valves for said operating medium, one of which is adapted to be actuated to lower the seat, another to raise the seat, another to recline the back and another to move the back into its vertical position, a manually-operable governing means for actuating said valves, automatic check valves associated with the back cylinder and arranged so that they will be actuated by the operating medium admitted to said cylinder, and a locking device for holding the back in adjusted position controlled by said governing element.

21. A chair provided with a seat, a socket, a hollow stem in said socket that carries said seat, a pump for circulating an operating medium that is used to raise said stem, a valve box provided with ducts and passageways through which said operating medium circulates, two separate control valves in the valve box, one of which is adapted to be opened to admit the operating medium to the socket and the other adapted to be opened to permit the operating medium to pass from the socket into the stem, and a manually-operable governing shaft in said valve box provided with means for opening said valves.

22. A chair provided with a seat, a back, a socket, a hollow stem in said socket that carries the seat, a casing at the upper end of said stem arranged inside of the seat frame and communicating with the interior of the stem, a cylinder inside of said casing provided with a piston for moving the back relatively to the seat, a pump for circulating an operating medium that is used to actuate said stem and piston, a valve box having internal ducts and passageways through which the operating medium circulates and external ports through which the operating medium can escape into said casing, control valves and check valves for governing the admission and exhaust of the operating medium to and from the socket and to and from the cylinder, and a manually-operable governing element on the seat frame provided with means for actuating said control valves.

23. A chair provided with a seat, a back, a socket, a hollow stem in said socket that carries the seat, a casing at the upper end of said stem arranged inside of the seat

frame and communicating with the interior of the stem, a cylinder inside of said casing provided with a piston for moving the back relatively to the seat, a pump for circulating an operating medium that is used to actuate said stem and piston, a valve box having internal ducts and passageways through which the operating medium circulates and external ports through which the operating medium can escape into said casing, control valves and check valves for governing the admission and exhaust of the operating medium to and from the socket and to and from the cylinder, a manually-operable governing element on the seat frame provided with means for actuating the control valves, a spring-actuated clamp that cooperates with the piston of said cylinder to hold the back in adjusted position, and means for rendering said clamp inoperative when said governing element is moved into certain positions.

24. A chair provided with a seat that is adapted to be raised and lowered, a back that is adapted to be reclined and straightened, a pump for circulating an operating medium that is used to move the seat and to move the back relatively to the seat, valves for controlling said operating medium, an electric motor for driving said pump, a manually-operable governing element for actuating said control valves, said governing element having a handle that is adapted to be moved into a plurality of different positions, and a switch for the motor circuit comprising a circuit closing device and a retaining device for the handle of the governing element combined in such a way that movement of said retaining device into its inoperative position causes said circuit closing device to become inoperative.

25. A chair provided with an adjustable seat, an adjustable back, an operating means for moving the seat and for moving the back relatively to the seat comprising an electric motor, a manually-operable governing element for said operating means that is adapted to be moved into a plurality of different positions, a retaining device for said governing element, a switch for the motor circuit provided with a movable circuit closing device, and a resilient means combined with said retaining device and said circuit closing device in such a way that said circuit closing device will be moved with a snap action out of engagement with its co-operating contacts when said retaining device is rendered inoperative and will move with a snap like action into engagement with its co-operating contacts when said retaining device becomes operative.

26. A chair provided with a seat that is adapted to be raised and lowered, a back that is adapted to be reclined and straightened, a governing shaft for controlling the

adjustment of the seat and back provided with an operating handle, an electric motor forming part of the means that is used to adjust the seat and the back, a retaining device on said handle, a stationary part that co-operates with said retaining device to hold the handle in adjusted position, a switch for the motor circuit comprising a movable circuit closing device, a jointed structure that connects said circuit closing device with the retaining device on the handle, and springs that exert pressure on said jointed structure in such a manner as to cause the circuit closing device to snap out of engagement with its co-operating contacts when the said retaining device is rendered inoperative and cause said circuit closing device to snap into engagement with its co-operating contacts when said retaining device is rendered operative.

27. In an adjustable chair of the type described, a manually-operable governing shaft, a handle on said shaft that is adapted to be arranged in a plurality of different positions, a pivotally mounted retaining device on said handle, a stationary part that co-operates with said retaining device to hold the handle in adjusted position, an electric circuit switch provided with a movable circuit closing device, a spring-actuated,

jointed structure on said handle that carries said circuit closing device, a link that connects said jointed structure to said retaining device, a resilient means that normally exerts pressure on said retaining device in a direction to hold it in engagement with the stationary part with which it co-operates, and a manually-operable means for disengaging the retaining device from said part. 35

28. In a chair of the type described, a manually-operable governing shaft provided with a handle, a pivotally-mounted retaining device on said handle, a stationary part with which said retaining device co-operates to hold the handle in adjusted position, means on said handle for disengaging said retaining device from said stationary part, ears on said handle, two links pivotally mounted on said ears on a common pintle, springs connected to said links in such a way as to normally hold them in an angular position with relation to each other, a circuit closing device pivotally connected to one of said links, means for connecting the other link to said retaining device, and a resilient means that exerts pressure on said retaining device in a direction to force it towards said stationary part. 40 45 50 55
